UNITED STATES PATENT OFFICE.

FRANK TAMBORELLO, OF MILWAUKEE, WISCONSIN.

DELIVERY CABINET.

Application filed March 23, 1923. Serial No. 627,024.

To all whom it may concern:

Be it known that I, FRANK TAMBORELLO, a citizen of the United States, and resident of Milwaukee, in the county of Milwaukee and State of Wisconsin, have invented certain new and useful Improvements in Delivery Cabinets; and I do hereby declare that the following is a full, clear, and exact description thereof.

10 This invention relates to an automatic delivery and receiving box. It comprises a cylindrical cabinet and a rotor therein divided into compartments, each adapted to receive goods delivered. The rotor may be 15 swung to discharge position wherein the housewife has access to the filled compartments through a door.

The main object of the invention is to 20 provide a receptacle of this character which is designed especially for use in apartments or dwellings where the occupants are away for the greater portion of the time, so that collections and deliveries may be made without inconvenience and which is so constructed 25 ed that it can be turned in one direction only and when the various compartments are filled the door of the receptacle will be automatically locked and can only be opened with a key.

30 An object of the invention is the provision of a cabinet that is portable and readily moved from place to place so that it may be conveniently carried into the house or deposited on a porch or in any 35 other suitable location.

Another object is to provide a receiving receptacle for protecting the articles placed therein from the elements as well as from tampering by thieves.

40 A further important object of the invention is the provision of a rotor having a low cylindrical wall which permits the ready insertion into the compartments of goods delivered and at the same time protects the 45 goods from contact with the cylindrical cabinet wall which otherwise might upset bottles and tear packages.

The cylindrical wall serves further to 50 impart strength and durability to the construction.

An object of the invention is the provision of a lever and pallet adapted to co-operate with a ratchet for advancing the 55 rotor, a link connecting the lever to the delivery door. The arrangement is such that

considerable leverage is exerted at the time of initiation of movement of the rotor.

With the above and other objects in view, which will appear as the description proceeds, the invention resides in the novel construction, combination and arrangement of parts substantially as hereinafter described and more particularly defined by the appended claims, it being understood that such changes in the precise embodiment of the 60 herein disclosed invention may be made as come within the scope of the claims.

65 In the accompanying drawing is illustrated one complete example of the physical embodiment of the present invention constructed according to the best mode so far devised for the practical application of the principles thereof.

70 Figure 1 is a central vertical section through the cabinet showing the rotor partly in section.

75 Figures 2 and 3 are plans on the lines 2-2 and 3-3 of Figure 1 respectively.

Figure 4 is a detail of a stop.

80 Figure 5 is a detail of a ratchet member and pawl for preventing rotation in one direction of the rotor.

85 Figure 6 is a detail of means for advancing the rotor.

The cabinet comprises a cylindrical wall 85 10 rigid with bottom 11 and top 12. A door 13 is hinged to the cylindrical wall at 14, overlying an opening therein. Through this opening the housewife may remove the goods on the removal of padlock 15. A delivery door 16 is hinged at 17 and overlies a second opening in the cylindrical wall 10. Bottom 11 carries a bearing 18 receiving a trunnion 19 and top 12 carries a bearing 20 receiving trunnion 21. Trunnion 19 is 90 rigid with disc 22 forming the bottom of a rotor. From disc 22 a plurality of radial partitions 23 extend upwardly and terminate at and are rigid with disc 24. Disc 24 is rigid with ratchet 25. The lever rotates 95 on trunnion 21 and carries a pallet 27 adapted to engage with the teeth of the ratchet, which are of the same number as the partitions. A link 28 is connected at its ends to lever 26 and delivery door 16. On the 100 opening of the delivery door pallet 27 is actuated to advance the ratchet and the entire rotor. Since in the closed position of the door lever 26 is almost at right angles to link 28, considerable leverage is exercised 105 110

through the medium of the door tending to put the rotor in motion. This facilitates the movement of the rotor and the opening of the door. The opening of the door advances the rotor in such wise as to position a compartment between two successive partitions immediately at the delivery opening. The goods may then be deposited on disc 22. The door is then closed by the individual making the delivery and lever 26 is swung to the position shown in Figure 2, wherein pallet 27 is operative to engage the teeth of the ratchet for again advancing the rotor on the opening of the door. The pallet is urged into engaging position by spring 29. During the movement of the rotor, the goods are held in safe position by a low cylindrical wall 30, which is rigid with disc 22 and contacts with the outer edges of partitions 23. Cylindrical wall 30 permits the ready insertion of the goods and protects them from being swung against the wall 10 of the cabinet by centrifugal force. There is thus no danger of upsetting the bottles, or tearing of packages. After one compartment has been filled, a second individual making a delivery moves door 16 open, as described, and thus advances the rotor. The movement of the door results in the carrying away of the goods deposited by the person previously making delivery. The second individual has access only to an empty compartment. The direction of movement of the rotor cannot be reversed, as a pawl 30 is carried by the lower face of disc 22 and cooperates with annular ratchet member 31 secured to bottom 11. The pawl permits the advancement of the rotor, but prevents reversed movement.

If all the compartments are utilized in delivering, the door 16 cannot be opened, as a stop 32 projects downwardly from disc 22 and on the completion of one revolution contacts with a rod 33. The housewife, in removing the goods, may withdraw the rod against the action of a spring 34 contacting at one end with a collar 35 on the rod and

at the other end with the wall of a housing 36. The retraction of the rod permits the free rotation of the rotor. It is impossible 50 for thieves to remove goods from the delivery opening, as the rotor is incapable of reverse rotation and compartments containing goods cannot be moved forwardly to the delivery opening, as the stop 32 will contact 55 with rod 33. The rotor may be emptied by the housewife and the stop 32 moved beyond rod 33, so that a complete rotation of the rotor is again possible.

The rotor is constructed strongly, the partitions 23 being secured to disc 24 by screws 37 and cylindrical wall 30 cooperates with the partitions and disc 22 to impart strength.

I claim:

1. The combination of a cabinet having 65 an opening therein for the delivery of goods and a second opening therein for the removal of goods, a door for closing said first mentioned opening, a door for closing said second opening, a rotor pivoted to rotate in 70 said cabinet, a pivoted lever, a pallet on said lever, a ratchet rigid with said rotor and a link connected at one end to said lever and at the other end to said door, said lever being almost at right angles to said 75 link when said door is in closed position.

2. The combination of a cabinet having a door opening thereinto, a rotor revolvably mounted within said cabinet and having a plurality of compartments adapted to be 80 successively positioned adjacent said door, a ratchet wheel carried by said rotor, a pawl operated from said door for advancing said ratchet wheel and thus advancing said compartments successively upon opening of said door, a stop adapted to limit rotary motion of said rotor after all of said compartments have past said door, and a second door giving access to said rotor and to said stop.

In testimony that I claim the foregoing 90 I have hereunto set my hand at Milwaukee, in the county of Milwaukee and State of Wisconsin.

FRANK TAMBORELLO.
